STOKING APPARATUS ASH REMOVAL
MEANS

Chester E. Shaffer, Arlington, N. J., and Albert Boyd Fisher, Jr., Wilkinsburg, Pa., assignors to Koppers Company, Inc., Pittsburgh, Pa., a corporation of Delaware

Original application March 15, 1940, Serial No. 324,048. Divided and this application August 1, 1945, Serial No. 608,232

4 Claims. (Cl. 110—165)

1

The present invention relates to the domestic-heating art. More particularly, the present invention relates to the ash-removal means disclosed in our Patent No. 2,388,294 granted November 6, 1945 of which this application is a division.

The domestic heating furnace described in Patent 2,388,294 comprises apparatus for automatically withdrawing solid fuel from a nearby storage bin by a conveyor, delivering the fuel to an underfed stoker tube through which the fuel is forced into a fuel bed supported upon an oscillatory grate. The oscillating movement of the grate acts to work ash and clinker through the fuel bed to the grate and to break up and force the ash through the grate into a furnace hearth under the grate. From the hearth the ash is positively moved into an ash-pit.

In the coke stoker illustrated in Patent 2,388,294 fuel is burned in the bed continuously and a single motor is used for operating all movable parts used in feeding the coke and disposing of the ash. The fuel feeding mechanism and the ash-removing mechanism are not operated continuously, but are put into operation to feed fuel to the fire bed and remove ash from the fire bed and furnace hearth when the consumption of fuel in the fuel bed has lowered the surface of the bed below a predetermined level. When the fuel feeding operation tends to increase the surface level of the fuel bed above a predetermined point the operation of the mechanism is discontinued.

The primary object of the present invention is to provide an apparatus for moving the ash from the furnace hearth to an ash disposal pit which is simple and dependable in operation.

Another object of the invention is to provide an apparatus for moving ash from the furnace hearth to a disposal pit which is quiet in operation and effective irrespective of the type of ash to be disposed of.

The invention has for further objects such other improvements and such other operative advantages or results as may be found to obtain in the apparatus hereinafter described and claimed.

In the accompanying drawings forming a part of this specification and showing for purposes of exemplification a preferred apparatus in which the invention may be embodied and practised but without limiting the claimed invention specifically to such illustrative instance or instances;

Fig. 1 is a partial plan view with parts broken away, of the furnace-grate, the stoker, the conveyor means for feeding fuel from storage to the grate, the ash-bars, and the actuating means for operating the fuel feeding and ash removing apparatus.

2

Fig. 2 is a side elevational view with parts shown in section taken on the line IV—IV of Fig. 1 and showing the adapter-member whereby fuel moved from the storage bin by the conveyor is introduced into the underfeed stoker, the figure also showing in full lines one of the ash-bars 91 of the present invention, and their operating connections, and also showing their orientation relative to the ash disposal pit;

10 Fig. 3 is a vertical sectional view taken along the line V—V of Fig. 1;

Fig. 4 is a plan view of the feed-tube of the stoker member with parts broken away to show details of its interior construction and the improved ash-bars of the invention, and the ash-pit.

15 Fig. 5 shows in diagram electrical circuits employable in actuating the instant system for feeding solid fuels to domestic furnaces according to the present improvement.

20 Figure 6 is an isometric diagrammatic view of the ash removal apparatus with other apparatus of the stoker broken away showing the driving mechanism.

As the present invention is of general application, for example, it may be used with various other types of stoking apparatus, as well as being of especial utility with the type of apparatus of our aforesaid Patent No. 2,388,294, which is hereby expressly made a part hereof by cross-reference thereto, a brief description herein of only so much of the general features thereof as is essential to an understanding of the present invention will suffice for an understanding of the same.

25 35 The same reference characters used in said Patent No. 2,388,294 will be used herein to designate the same parts in each of the several views.

The conveyor means for transporting fuel in a horizontal plane between the bin and the 40 stoker members of the unitary system comprises plate 31 that is reciprocally mounted in a sheet metal housing 32, Figs. 1 and 2. It is slidably supported above the bottom of its housing 32 on metal strips that serve as tracks. The said conveyor-housing 32 extends from a coke-bin to the stoker inlet. Metal-covered wooden strips 34 are affixed to the walls of conveyor-housing 32 and the wooden strips 34 form a sort of recess in which the reciprocating conveyor-plate 31 is ac-

45 tuated, and have the effect of directing all fuel that flows into the bin-trough only onto said plate's upper surface.

Beneath the reciprocating plate 31 of the conveyor and affixed thereto at its outer end is connecting-rod 36, Fig. 1 whereby it is actuated by the electric motor that is adapted to operate the 55 unitary system, said connecting-rod being at-

tached to the conveyor-plate 31 by means for increasing or decreasing the amount of movement imparted to the conveyor-plate during each stroke of the connecting-rod and, consequently, to regulate the quantity of fuel carried from the bin during each cycle of movement of the conveyor-plate.

The conveyor housing is provided, for purposes of cleanliness, with cover-plate 39.

Adjacent the discharge or inner-end of conveyor 30, the reciprocating plate 31 and the recess-forming members 34 therefor are both supported on the horizontal surface of the inlet to adapter-member 41, Figs. 1 and 2, that is held atop the stoker apparatus, and which serves to direct conveyed fuel downwardly onto the actual stoking device of said stoker. Cleats 40 allow free movement of the conveyor-plate 31.

Flexible finger 41 attached to the walls of adapter-member 41, as shown in Fig. 1, can be moved by its associated thumb-screw to restrict or increase the free-way for fuel flowing along the conveyor-plate 31 and serves as means for obtaining fine regulation of the quantity of fuel delivered from storage to the stoker during any period.

Adapter-member 41, for directing conveyed fuel into the stoker apparatus, is supported in the circular inlet to the stoker tube by means of screws 43 as shown in Fig. 2; in consequence of this arrangement, the adapter and its associated conveyor are pivotable around the stoker-inlet and can be thus arranged at a diversity of angles to the stoker and the furnace.

As also shown in Fig. 2, a damper valve 44 is installed at the inlet side of said adapter-member 41 to close the air passage between the conveyor and the stoker during such times as fuel is not being introduced into the latter, thereby to prevent combustion-air being drawn into the furnace through adapter 41 and stoker tube 52 when they are only partially filled with solid fuel at any interval. As shown in Fig. 2, damper-valve 44 is supported at its top by a hinged arrangement to the walls of adapter 41 adjacent its inlet. Finger 45 depending from one end of the hinge-pin serves to open and close said damper-valve, said finger being automatically actuated by arm 46, that is attached to and moves correspondingly with connecting-rod 36 in such manner that during the forward stroke of the connecting rod, when coke is being delivered to the stoker, the damper is opened and conversely is closed on the return stroke of said connecting-rod. As connecting-rod 36 is always at the end of its back stroke when the unitary system is at rest, damper-valve 44 is in opened position only at such times as fuel is being delivered to the stoker. Counterweights 47 are employed to close and insure a close sealing of the damper-valve.

Removable plate 48, which is attached to and forms the top of the adapter-member 41, supports, in a threaded hole the bolt 81 which has a lock-nut and carries the principal metallic covering 63 for the working parts of the assembly.

Referring now to Figs. 1 and 2, the stoker apparatus with which is incorporated the present invention is of the underfeed type and comprises a casting 52 having a relatively extended, horizontal section that, beneath the furnace-grate, terminates in substantially a right-angle bend on the upper surface of which there is supported a removable extension-ring 63, the vertical section of the stoker-tube and said extension-ring

being flared slightly outwards, thereby to facilitate flow of fuel through the tube and impede backward movement of such thereof as has been elevated above its horizontal section.

Casting 52 is essentially a hollow, cylinder-like body whose top and side walls are of continuous metal construction. In the bottom of the casting, there is a large rectangularly-shaped opening that extends from directly beneath its fuel inlet up to a point somewhat short of its upward sweep. The member 52 is lined with replaceable liner-plates 53 that cover most of the lower part of the side walls of the tube and are conveniently formed of cast iron, hard-surfaced steel, or other appropriate material. These plates 53 are of greater thickness adjacent the fuel inlet of the stoker-tube than they are further therealong, as shown in Fig. 4, their vertical edges thus forming a sequence of ridges or offsets that have the effect of presenting to the solid fuel as it traverses the casting in the direction of the grate, tube-sections of increasing cross-sectional area which facilitate the stoking operation and tend to restrict any backward movement of the stoked fuel during the backward stroke of the reciprocating stoker-plate 51.

Reciprocally mounted within the tube-casting 52, and forming a substantial portion of its lower wall, is the stoker-plate 51 which, adjacent the inlet-end of said tube-casting, is mounted on cross-head 71 of the driving mechanism for the unitary system and extends through a provided slit in the adjacent end-wall of said casting. At its opposite end, said stoker-plate is rigidly affixed to the upper surface of ram-head 59, the said cross-head, plate, and ram-head being all arranged for reciprocatory movement as a unit. The shelf-like ridges 62, shown in Fig. 3, on the inner walls of the tube-casting form a track for the stoker-plate during its reciprocatory movements.

Removably mounted in the lower wall of the stoker-tube adjacent its upward bend, is the finger-bar 61 which is retained in position by means of its attached lug that slidably fits into a corresponding opening in the walls of the stoker-tube. As clearly shown in Figs. 2 and 3, ram-head 59 is formed with a median groove which permits it to move freely backwards and forwards over the stationary finger-bar which serves the function of aiding in the support of the vertical column of fuel above it during the backward stroke of the ram-head.

Lugs 54, 55, formed integrally with the stoker-tube casting have threaded holes containing bolts 56 whose heads serve as feet for said casting and whereby the stoker can be levelled.

That lower wall-portion of the stoker-tube, adjacent the point where the stoked fuel undergoes a sharp change of direction, is naturally subjected to heavy abrasive action by the fuel. It has therefore been found expedient, for lengthening the operative life of a stoker-tube, to form its walls in this part of extra thickness of metal, as shown in Fig. 2; in the same figure, there is also clearly illustrated rib 133 that is cast integrally with the stoker-tube walls and which, in combination with the hereinabove described finger-bar 61 and also the adjacent offsets formed at the termini of liner-plates 53, assists in supporting, above the normally only partially filled horizontal section of the stoker-tube, that vertical column of fuel which is about to be elevated into the fuel-bed by the movements of the reciprocating ram-head 59.

The upper edge of extension-ring 63 is flanged and presents a smooth surface whereon there is rotatably supported, by means of a co-acting groove, the grate 60 of the unitary system. For simplicity of fabrication, the grate can be formed of sections having integrally-cast lugs 66 whereby said sections can be bolted together to form a single rotatable unit. The smooth upper surface of said grate lies in substantially a horizontal plane and its slotted perforations 98, that extend through the body thereof for the removal of ashes from and for the admission of combustion air to the fuel bed, are arranged in groups according to a barred pattern wherein each has at least one slot substantially radially disposed whereas the remainder are in parallelism therewith.

Directly beneath the grate for which it can function as means to prevent tipping of the former in the event of unequal loading, or the like, but operatively independent thereof, is the ash-ring 80 which is supported by radial brackets 85 that are themselves supported at their inner ends on the outer walls of extension-ring 63. Ash-ring 80 is formed of arc-like sections bolted together, the ends of such sections having slot-like openings that permit adjustment of its overall diameter, so that its periphery can be made substantially equal to that of the grate or be increased somewhat thereover. This feature of extensibility of said ash-ring is of special importance in that it permits the employment of a grate of some standardized dimension in an existing furnace having a fire-box of which the internal diameter is so much greater than that of the grate that otherwise excessive leakage of ash and of fuel would take place in the peripheral space therebetween. The closing of this peripheral space by the ash-ring is susceptible of further refinement by supporting thereon, during the installation of the apparatus, a seal 84 formed from an asbestos cement, or the like.

In accordance with the present invention, after ashy combustion residues have passed through the slots 98 of the grate, they are removed from the floor or hearth of the furnace under the grate and carried therefrom to an ash pit or receptacle 95 by means of the hereinafter described ash-removal apparatus.

Referring particularly to Fig. 6 in which the ash removal apparatus is shown isometrically and separated from other components of the unitary system, the motor 112, gear reducer 113, crank arm 114 and lever 115 provide the reciprocating driving force to the ash removal apparatus. Interconnected for simultaneous reciprocal movement from the lever 115 is the cross-head 71, member 134 and stoker plate 51 to the underside of which is attached the vertically disposed connecting bar or post 99. A cross-head 64 depends from the said post 99. A pair of reciprocating slide bars 91 as shown in Figs. 1, 2, 3, 4, and 6 are pivotally secured to the cross-head 94 with which they move backwards and forwards in unison. Adjacent their opposite ends, the bars 91 are slidably held in guides 93 therefor which are spaced apart a distance greater than that obtaining between the said bars' pivots on their cross-head. During their reciprocatory movement the ash-removal bars are thus provided with some lateral as well as lengthwise movement, the former said movement serving to clear the path through the accumulation of ashes that are retained in a pile on the floor of the furnace within the restrictive area defined by the furnace walls. The said path so-cleared by the lateral

movement of the slide-bars 91 is wider than the bars, so that any of the ashes falling upon their upper surfaces can be moved along such surfaces and out from the furnace-hearth without being brushed off by adjacent material of the ash-pile.

As shown particularly in Figs. 3 and 6, longitudinal guide plates 155 having integral cover plate 155A are mounted at each side of the stoker tube 52 and extend along the sides of the slide bars 91 from the hearth to the ash receptacle or ash-pit 95. The ash which is moved from the furnace hearth toward the ash-pit moves between the guide plates 155, and the side walls of the said guide plates support ash lying at approximately its angle of repose from the sides of the guide plates down to a trough extending longitudinally along the slide bars 91. The guide plates 155 confine the ash within a channel extending from the hearth to the ash-pit and assist the bars 91 in directing the ash from the said hearth to the ash-pit essentially by retaining the ash along the sides of the slide bars 91 in much the same manner as the furnace wall retains the ash in a pile on the hearth. Ashes extracted from the furnace hearth, by the movement of the ash-removal bars, drop from their surfaces into ash-pit 95 and into a therefrom removable container, if preferred.

The integral cover plate 155A prevents the flow of excess air into the furnace hearth through the opening required for ash removal. Cooperating to prevent uncontrolled inflow of air through furnace-hearth openings to the grate is a tightly fitted metal plate 92 which fills the space customarily covered by an ash-pit door and fits closely around the stoker tube and ash-removal apparatus. Fitted against the plate 92 as it extends from the face of the furnace and smoothly joining the same to the furnace walls is a further section of the overall sheet metal stoker-cover 83.

In its embodiment shown in the drawings, the present unitary system is arranged for actuation in response to fuel requirements of the fuel-bed to keep the same at a constant level. Means for accordingly actuating the unitary system comprises geniculate rod 101 to which is affixed at its lower end a truncated metal body 102, preferably formed from such resistant alloy as "Ni-Resist," or the like, that is in constant contact with the upper surface of the fuel-bed, said rod being pivotally mounted on a bracket for movement in a vertical plane, so that the member 102 can easily follow small changes in the level of the upper surface of the fuel-bed. Counterweight 103 is adjustably mounted on the outer end of rod 101 thereby increasing its ease of movement and sensitivity to changes in the fuel-bed level and also functioning to prevent the said rod's own weight causing its sinking below the surface of the bed. Adjustably affixed to the said geniculate rod where it extends through switch-box 104, there is an electrical switch, preferably of the Mercoid type, that is included in the circuit for driving electrical motor 112 whereby the unitary system is actuated. The said switch is disposable to open or close said circuit when the upper surface of the fuel-bed has respectively been for any reason raised or lowered beyond a predetermined level. The opening of said electrical switch however does not necessarily stop motor 112 immediately, unless the driving rod 115 for the assembly is at the end of a full backward stroke, as will be hereinafter set forth.

The above-described features of the system are all interconnected for simultaneous movement by means of electrical motor 112 operative through speed-reducer 113, crank-arm 114, and the single driving-rod or lever 115, all of said members being mounted on the basal casting 111. Pivotedly attached to lever 115 and adapted to be reciprocally moved thereby is cross-head 71 to which is bolted the one end of stoker-plate 51 that reciprocates inside of stoker-tube 52.

All of the driven parts of the apparatus, that is, conveyor member 31, stoker-plate 51, ash-bars 31 and grate 60, are arranged to communicate directly or indirectly with the said driven cross-head 71. Viewing Fig. 1 from that end thereof adjacent the actuating motor, there is observed at the right-hand side of the cross-head 71 a thereto affixed arm containing an extended obtuse-angled slot 116 which terminates at its upper end in a short transverse slot. By means of the illustrated bolt that can be slid along said slot 116 and secured at any preferred position therein, link 117 is pivotally secured to said cross-head and serves as a connecting arm whereby reciprocatory motion of the cross-head is utilized to reciprocate the two cranks 118, disposed at right angles to each other, about their own pivot, which is supported in the bracket 121 attached to the lower side of the adapter-member 41. In the apparatus from which the present drawings, as well as those of the aforesaid parent application, were made, the two cranks 118, shown at right angles to each other in Fig. 1, were, as indicated therein, adjustable to any angle, about their own pivot, so that when the angle of approach of the conveyor to the stoker is changed, the angle between the crank arms 118 may be changed. Through this lever system, reciprocatory movement of the cross-head is resolved into similar movement of connecting-rod 36 which actuates the fuel conveyor-plate 31. The particular shape of obtuse-angled slot 116 and the adjustable angle between cranks 118 makes it possible to dispose conveyor-plate 31 at a wide range of angles-of-approach to the stoker inlet and yet to employ the motion of member 71 for operating the conveyor-plate to feed the stoker.

Operatively connected with the opposite end of cross-head 71 is the train of co-operative devices whereby the furnace-grate 60 is, accordingly, made adjustably rotatable about its vertical axis, as there is required a greater or lesser removal of ashy residues, and the like, from the fuel-bed during any period of combustion. Within linear slot 72 of the cross-head, the effective length of said slot, as is clearly visible in Fig. 3, being simply regulable by means of a screw bolt 73 that is adapted for movement longitudinally thereof, the pin 79 is adapted to slide freely independently of the cross-head a distance determined by and regulable according to the accorded space between the end of said bolt 73 and its adjacent slot-end and the said end of the bolt and said slot-end are adapted to engage said pin at some point during respectively the backward or forward movement of the reciprocatory cross-head, and in so doing, to move in the same direction the link 74 which is pivotally moveable at both its ends. Movement of said link 74 by pressure of the cross-head thereagainst effects corresponding movement of link 70 that is supported on a bracket, projecting from walls of the under-feed-tube, by the bolt 100 which also serves to support for movement independently of said link 75 of the cross-head.

76 the ratchet 67 which is rotatable around said bolt.

Spring actuated click 68 and pawl 69, of which the former is mounted on a pin for independent movement on lever 70 whereas the latter is similarly mounted on the above-mentioned bracket affixed to the walls of the stoker-tube, are so disposed in respect of the teeth of the ratchet 67 that pawl 69 engages a tooth thereof during the 10 forward stroke of the cross-head thereby allowing lever 70 similarly to move about pin 100 independently of the ratchet and the click 68 to advance in the direction of pawl 69 a number of teeth that is regulable by the effective length 15 of slot 72, and during the backward stroke of the cross-head, click 68 under the influence of its actuating spring is arranged to engage the adjacent ratchet-tooth so that both ratchet and the lever 70 are simultaneously moved in a counter clockwise direction. During backward movement of the cross-head, pawl 69 slides over the moving ratchet-teeth.

By means of the above-described train of apparatus, the reciprocatory movement of cross-head 71 is translated into an intermittent moving of the ratchet always in a counter clockwise direction. During its rotation around pin 100, the ratchet carries with it link 75 mounted thereon by pin 78 and about which said link is rotatable. At its opposite end, the link 75 is rotatably attached to one end of the centrally-pivoted lever 65 on either end of which an adjustable lever-rod 76 is pivotally mounted, the opposite ends of said rods 76 being also pivotally mounted 35 on shoulders 77 that are cast integrally with grate 60 on its lower surface where they are disposed along a diameter and whereby said grate is provided alternately with a clockwise and counter clockwise movement in a horizontal 40 plane.

Rotation of ratchet 67 moves link 75 in alternation forward and backward thus respectively pushing and pulling that portion of member 65 to which it is attached and thereby causing said member to oscillate on its pivotal mounting and move the grate member alternately in opposite directions in a horizontal plane.

The total movement of the grate in any one direction is accomplished in sequences of step-wise movements whose lengths are variously adjustable, thereby enabling the householder to increase or diminish the amount of agitation, incidentally imparted to the fuel-bed, in accordance with the combustion results he wishes to effect with an individual fuel. This feature of adjustability of grate-movement is of important advantage for promoting the automatic delivery of heat over protracted periods because it permits either a regulable removal of combustion-residues from the grate and, in consequence, the maintenance of a constant rate of consumption of combustible notwithstanding changes in the ash content of the employed fuels, or, in the case of any particular fuel, a removal of ash from the fuel-bed that can be either increased or decreased to respectively enhance or diminish accessibility of combustion air to the burning fuel and correspondingly alter the rate of consumption of its combustibles. This is all simply and easily effected by suitable adjustment of screw-bolt 73 to regulate the effective length of slot 72 of cross-head 71, which in turn controls the number of teeth of the ratchet over which click 68 passes before becoming engaged for the backward stroke 70 of the cross-head.

As hereinbefore mentioned, perforate slots 98 of grate 60 are arranged in a particular barred pattern wherein the slots are disposed substantially on or parallel with a diameter of the grate and the remainder in substantial parallelism with them. During the grate's rotational movements about the axis of its supporting extension-ring 63, successive contacts of the wall-edges of slots 98 with the fuel or ash particles lying adjacently thereabove tends, in consequence of their changing angle of incidence in respect of surface irregularities of such materials, to provide said particles with rotational movement around their own axes in addition to that motion which is contributed by the grate itself. Such rotational movement is of course most pronounced near the grate periphery where the ash content of the fuel-bed tends to be the highest and therefore the greatest agitation of the fuel-bed is needed to remove the ash sufficiently rapidly therefrom to prevent its fusion into large size clinkers. To the lower surface of any such clinker as does form on top of the grate, the said changing angle of incidence with which a succession of slots comes into contact therewith tends, assisted by the weight of the fuel-bed thereabove, to shear the clinker into fragments capable of passing through the grate-slots and being discharged from the installation by means of ash-bars 91. The facility with which the apparatus is operative to maintain a clean fuel-bed, i. e. one that is relatively free of ashy residues and clinker, and from which such residues are continuously and automatically removable for extended periods, is, it is felt, in large part the result of this particular configuration of the grate-slots and the resultant special movement contributed by it to the fuel-bed, in combination with the regulability of the length of the steps with which the grate is moved between its limits of travel.

Mounted on basal casting 111 of the stoker apparatus is switch box 131 that contains a Mercoid switch which is itself supported on rotatable finger 132, said finger being under the influence of a spring member that always returns it, when moved therefrom, to a pre-arranged position and carries with it the Mercoid switch which, in the pre-arranged position of the finger, is supported in such manner as to close the electrical circuit. Finger 132 is also so disposed that, during each backward stroke of cross-head 71, the outer end of that extension therefrom containing slot 116 moves said finger about its supporting shaft in the same direction, thereby tipping the attached Mercoid switch into a position to break flow of current therethrough. On the forward stroke of said cross-head, finger 132 and its associated switch are returned to the reverse position by the spring attached thereto. Connected in parallel with the Mercoid switch in box 131 is a similar switch that is contained in switch-box 104 and is arranged for movement, by the upward and downward movement of fuel-bed-level control 101, between positions adapted to open and close the electrical circuit to motor 112 respectively as the fuel-bed is stoked to reach a preferred level or sinks therebelow.

The connection in parallel of the two Mercoid switches of members 104, 131, thus provides for the delivery of power to the driving motor at all times save when both switches are simultaneously in a position to open said circuit, and by its means power continues to be delivered to the motor, even after that switch of the fuel-bed-level control has opened the circuit in its included branch line, un-

til driving-rod 115 is at the end of its backward stroke when both switches and the motor-circuit will be in open position until member 102 again sinks with the fuel-bed level and moves the therewith communicating switch of 104 to close the circuit to the motor.

This feature whereby driving-rod 115 can come to rest only at the end of its backward stroke assures, upon its restarting, that motor 112 is always under the least possible load, thereby, at that instant, insuring against heavy current flow and damage to the motor of which the size required depends upon its starting-load.

Members 151, 153 and 154 of Fig. 5 represent respectively circuit fuses, the lines that serve as a source of power, and a power-line switch.

The working parts of the assembly are all encased in a sheet-metal covering 83 to enhance its appearance and protect its working parts. Above 20 adapter-member 41, a portion of said covering is formed as a removable cover-plate that provides ease of access to the several mechanical features.

The ash-bars 91, that are attached to the lower part of reciprocatory stoker-plate 51 are correspondingly reciprocated with the latter, all said members being actuated from cross-head 71 and in such manner that those employed for conveying materials all move simultaneously in a forward or return stroke.

25 By the reciprocatory motion of the ram-head 53, new quantities of the employed fuel are elevated into the vertically-extending section of the stoker-tube and displace that already there into the fuel-bed atop grate 60, the inflow of such fuel 30 giving more especially the center of the fuel-bed a measure of agitation and causing a sort of radial flow outward of the fuel particles already therein.

At the same time that the conveyor-plate 31 40 and stoker-plate 51 are performing their operations, the grate is being moved either clockwise or counter clockwise in steps of regulable distance along an arc of the circle defining the outline of the grate, thereby revolving and rotating between 45 themselves those particles of unburned fuel and ash closer to the periphery of the grate, such movements causing the fine particles of ashy residues to fall through the interstices of the fuel-bed and the grate-slots 98 onto the furnace-hearth therebelow where they are picked up on the upper surfaces of the simultaneously reciprocating ash-bars 91 and moved out of the hearth space toward the front of the furnace whence they fall into ash-pit 95. When sufficient new fuel has 50 been introduced into the fuel-bed to raise member 102 to a predetermined level, the Mercoid switch, in switch-box 104, will be moved to stop current flow therethrough whereupon, during the subsequent backward stroke of driving-rod 115, contact 55 in the Mercoid switch of switch-box 131 will be broken and the system come to rest until the next demand for fuel by the level control.

In such unitary system for employing solid fuels, it is however insufficient merely to furnish 60 co-operative features of apparatus that are adapted to perform the above-stated operations, because the more common of such fuels vary from one to the other in certain of their characteristics; notably, their ash contents. It is, 70 therefore, highly desirable for the assurance of continued automatic operation over a protracted period, that the component apparatus of such a system be not only co-operatively disposed but also that their individual operations be so regulably co-ordinable within the system that opera-

tive results of the one can be made consonant with that of another. For example, with fuel of a given ash content being consumed on the grate at an established rate and with a corresponding delivery thereof to the fuel-bed by the conveyor and stoker, an established angular movement of the individual steps of the grate in its rotary motion can provide just that amount of agitation to the fuel-bed necessary to give removal of ashes therefrom and from the grate that is adequate to keep apace with their formation, thereby assuring good conditions of combustion and non-formation of clinker that might otherwise accumulate on the grate to prevent combustion air reaching the fuel and thus extinguishing the fire. With such co-ordination of these apparatus of the system, excellent combustion conditions can thus be automatically maintained for an indefinite period. Let it now be assumed, however, that the source of solid fuel is changed to one having a higher content of ash but that it is still desirable to burn the combustible of the new fuel at the same rate as in the previous instance. This means that to deliver the same amount of combustible to the grate for a given period, a larger quantity of fuel will necessarily have to be conveyed to the stoker. In the system this is simply done by increasing the amplitude of movement of conveyor-plate 31 or by retracting finger 41 closer to the walls of the conveyor shell. In consequence of the fact that more ash will accumulate in the fuel-bed with fuel from this new source, it will become necessary, for the obviation of undue accumulations of such material in the fuel-bed, to increase the amount of agitation ascribed thereto by the grate in its stepwise movement. This circumstance is simply provided for by so moving threaded bolt 73 as to decrease the effective length of slot 72, that determines the extent of each angular movement of the ratchet, and which in turn will increase the angularity of each movement of the grate and the resultant agitation of the fuel-bed, thereby increasing the rate of ash withdrawal through the grate onto the hearth. With more rapid accumulation of ashes on the furnace-hearth ashes will be automatically piled higher on the top of the ash-bars 91 and during each cycle of their reciprocatory movement more ash will be carried to the ash-pit.

If, on the other hand, it is desired to employ more freely-burning solid fuel of sharply reduced ash content which makes it desirable to decrease the rate of ash withdrawal and even to allow a layer thereof to accumulate on the grate in order to reduce the natural draft, the stepwise movement of the grate can be reduced to establish such condition without altering an established setting of the conveyor 31; or, as is now obvious, with any given solid fuel, the extent of movement of the conveyor-plate 31 can be adjusted to meet the demands of the fuel-bed for any rate of its consumption, and the agitation thereof be arranged properly to remove the ash for such rate by co-ordinative adjustment of the grate movement to that of the conveyor-plate.

By means of the present improvements in stoker systems it is now possible to assure, for domestic-heating installations, apparatus whereby, for any solid fuel, an appropriate and precise adjustment is always establishable between the rate of fuel delivery, its rate of combustion, and the rate of ash withdrawal from the heating system, so that these factors are always in equi-

librium to give optimum combustion conditions for any of the common solid fuels.

The invention as hereinabove set forth is embodied in particular form and manner and may be variously embodied within the scope of the claims hereinafter made.

We claim:

1. The combination with a hearth under the grate of a heating furnace of an ash receptacle positioned adjacent the hearth and means for delivering ash from the hearth to said receptacle comprising: a driving member, a pair of longitudinally arranged bars mounted closely adjacent the hearth surface and arranged at an acute angle to one another with one end of each bar movably connected with the driving member, the other ends of the bars being slidably mounted and more widely separated than the driven ends, and means to reciprocate the driving member to move the bars longitudinally, the mounting of the bars being arranged to give both lateral and longitudinal movement to the bars during the reciprocating movement.
2. The combination defined in claim 1 in which the bars are flat and are mounted substantially parallel with the hearth surface.
3. In combination with a hearth under the grate of a furnace of an ash receptacle positioned adjacent the hearth and means for delivering ash from the hearth to the receptacle, said means comprising a driving member positioned over the receptacle, a motor having a crank connection for reciprocating the driving member, a pair of divergently arranged flat bars pivotally connected to the driving member, guides disposed under the grate and mounted to slidably support the bars at their divergent ends and guides mounted along the sides of the bars between the hearth and the ash receptacle to confine the movement of the ash from the hearth to the ash receptacle.

4. In combination with a hearth under a grate of a heating furnace, an ash receptacle positioned adjacent the hearth and means for moving ash residue from the hearth to the receptacle, said means comprising: a flat bar mounted for movement closely adjacent the hearth to move within ash upon the hearth, said bar having a plane, smooth upper surface, an actuating lever pivotally connected with one end of the bar, a guide for supporting the other end of the bar, means to impart a reciprocating movement to the actuating lever, the mounting of the bar being at an acute angle with reference to the line of reciprocation of the lever whereby the reciprocating movement will move the bar both longitudinally and laterally in advancing ash to the receptacle.

CHESTER E. SHAFFER.
